UNITED STATES PATENT OFFICE.

EDWARD BOOTE, OF EAST ORANGE, NEW JERSEY.

DESIGN FOR AN ARTICLE OF MANUFACTURE.

48,744.

Specification for Design.

Patented Mar. 21, 1916.

Application filed October 12, 1915. Serial No. 55,588. Term of patent 3½ years.

To all whom it may concern:

Be it known that I, EDWARD BOOTE, a subject of the King of Great Britain, residing at East Orange, in the county of Essex and State of New Jersey, have invented a new, original, and ornamental Design for an Article of Manufacture, of which the following is a specification, reference being made to the accompanying drawing, forming part thereof.

The figure is a plan view of my new design to be applied to an article of manufacture.

I claim:

The ornamental design for an article of manufacture, as shown.

EDWARD BOOTE.
